A. D. RHODES,
GAGE FOR POSITIONING SHEET MATERIAL,
APPLICATION FILED NOV. 29, 1919.

Patented Apr. 19, 1921.

22 25 F.C. 3.

Inventor:
Austin D. Phodes,
by his attorney,
Charles S. Gooding.

UNITED STATES PATENT OFFICE.

AUSTIN D. RHODES, OF WALTHAM, MASSACHUSETTS, ASSIGNOR TO AMERICAN LACING
HOOK CO., A CORPORATION OF NEW JERSEY.

GAGE FOR POSITIONING SHEET MATERIAL.

1,375,641.

Specification of Letters Patent. Patented Apr. 19, 1921.

Original application filed July 29, 1918, Serial No. 247,116. Divided and this application filed November 29, 1919. Serial No. 341,535.

To all whom it may concern:

Be it known that I, AUSTIN D. RHODES, a citizen of the United States, residing at Waltham, in the county of Middlesex and 5 State of Massachusetts, have invented new and useful Improvements in Gages for Positioning Sheet Material, of which the following is a specification.

This invention relates to a gage for positioning the edge of the upper of a boot or 10 shoe preparatory to having lacing hooks or eyelets set therein.

In setting lacing studs, eyelets or hooks in the uppers of boots and shoes, it is desirable to have a gage against which the upper edge of the upper may be placed in order to 15 locate said edge in the proper position relatively to the lacing hook or eyelet setting instrumentalities in setting the first hook or 20 eyelet in the upper and also to have said gage capable of being easily and automatically removed from the path of the upper as it is fed forward after the lacing hook has been set.

25 To these ends the invention consists of a gage of the character hereinafter set forth in the specification and particularly pointed out in the claims and furthermore of the combination of the gage with a presser foot 30 and work-support and means to move the presser foot away from the work-support or vice versa.

This case is a divisional case from a pending application filed by me on July 29, 35 1918, for gage for positioning sheet material, Serial No. 247,116.

Referring to the drawings:

Figure 1 is a plan view of my invention 40 illustrating the gage mounted on a work-support.

Fig. 2 is a front elevation of my invention showing the same in connection with a work-support and presser foot, the presser foot being shown in elevated position and a portion 45 of the upper of a boot being shown in position with its upper edge resting against the front edge of the gage.

Fig. 3 is a front elevation similar to Fig. 2, but illustrating a modified form of gage 50 embodying my invention.

In the drawings the presser foot and work-support are similar in their design and mode of operation to the work-support and

presser foot illustrated and described in Letters Patent issued to Arthur R. Havener 55 November 29, 1910, No. 977,090, "machine for setting lacing hooks," to which reference may be had for the mechanism whereby the presser foot is raised and lowered.

Like numerals refer to like parts throughout the several views of the drawings.

In the drawings, referring to Figs. 1 and 2, 5 is a presser foot which is fastened to a vertical, reciprocatory rod 6; 7 is a gage pivoted at 8 to a bracket 9 which is adjustably fastened to a work-support 10 by means of a screw 11 which projects through a slot 12 in said bracket 9 and has screw threaded engagement with the work support 10. The gage 7 has an arm 13 thereon at one end 65 thereof which projects upwardly through a slot 14 provided in the work-support 10 and has its uppermost end 15 arranged to bear against the work contacting surface 16 of the presser foot 5. The front edge of the 70 gage 7 has a notch 7' therein and has an inclined portion 17 which extends from the work contacting surface 18 of the work-support 10 upwardly and forwardly and which has another inclined portion 19 which extends rearwardly to the uppermost end 15 of said gage. The gage 7 is enlarged on the opposite side of the pivot 8 from the arm 13 as at 20 to form a counterbalance.

The operation of the device hereinbefore 85 specifically described is as follows: Assuming B-B to be the center line of the setting instrumentalities, the gage is adjusted longitudinally of the slot 12 until the front edge of the gage where it intersects the work contacting surface 18 of the work-support 10 is at the correct distance from the center line B-B or at the desired distance from the top of the edge of the shoe upper to the desired center of the first lacing hook to be set 95 therein. The operator holds the upper 21 in the position illustrated in Fig. 2, the presser foot being at this time raised with the upper edge of the upper contacting with the front edge of the gage adjacent to the work-contacting surface of the work-support. At this time, the uppermost end 15 of the gage 7 rests against the under surface or work contacting surface 16 of the presser foot and as the presser foot is lowered from the position illustrated in Fig. 2 to a position where

it clamps the work against the work-support the gage 7 will be rocked upon its pivot, the end 15 being pushed downwardly until the edge of the upper 21 rests against the part 5 19 of the front edge of the gage.

In the subsequent motion of the machine, as is well-known to those skilled in the art, the presser foot is raised just sufficiently to take the pressure off of the upper which is 10 then automatically fed forward and the rearwardly inclined portion 19 of the front edge of the gage allows the upper to be moved toward the left Fig. 2 and in so passing, the gage will be pushed downwardly by the upper and said upper allowed to pass to its new position to receive another lacing hook or eyelet.

It will be seen that when the upper is in the position illustrated in Fig. 2, if the 20 operator tries to push the upper toward the left, it will be impossible so to do, because the edge of the upper is located between the inclined portion 17 of the front edge of the gage 7 and the work contacting surface 18 25 of the work-support. When the parts are in the relative positions assumed thereby when the presser foot is slightly raised to allow the upper to be fed toward the left, the gage is pushed down by the upper and 30 passes downwardly out of line therewith, because the edge of the upper will at that time be engaging the rearwardly inclined portion 19 of the front edge of the gage.

In Fig. 3 a modified form of my invention 35 is illustrated which is the same as the form of my invention hereinbefore described and illustrated in Figs. 1 and 2, except that the gage 22 is not provided with a counterbalance but in order to hold the gage upwardly with its uppermost end pressing against the presser foot, a spring 23 is attached at one end to said gage and at the other end to a pin 24 fast to a bracket 25. The operation of this form of my invention 40 is the same as that of the form of my invention illustrated in Figs. 1 and 2.

I claim:

1. A work-support and a gage movably mounted thereon and adapted normally to 50 project above the work contacting surface of said work-support, and movable vertically relatively to said work contacting surface, the front edge of said gage being inclined upwardly and forwardly from said work- 55 contacting surface.

2. A work-support and a gage movably mounted thereon and adapted normally to project above the work contacting surface of said work-support, the front edge of said 60 gage being inclined upwardly and forwardly from said work contacting surface for a portion of its length above said surface and then rearwardly and upwardly to its uppermost end.

65 3. A work-support and a gage movably

mounted thereon and adapted normally to project above the work contacting surface of said work-support and through a slot extending longitudinally of said work-support, said gage being movable vertically 70 relatively to said work contacting surface, the front edge of said gage being inclined upwardly and forwardly from said work contacting surface.

4. A work-support, a bracket mounted 75 upon said work-support and adjustable longitudinally of said work-support and a gage movably mounted on said bracket and adapted normally to project above the work contacting surface of said work-support, the 80 front edge of said gage being inclined upwardly and forwardly from said work contacting surface.

5. A work-support and a gage movably mounted thereon and adapted normally to 85 project above the work contacting surface of said work-support, the front edge of said gage having a notch therein adjacent its upper end, said gage being adapted to move vertically relatively to said work contacting surface.

6. In combination a work-support, a presser foot, a gage movably mounted on said work-support and adapted normally to project above the work contacting surface 95 of said work-support and against said presser foot, the front edge of said gage being inclined upwardly and forwardly from the said work contacting surface and means to raise and lower said presser foot, 100 said gage being adapted to move upwardly and downwardly with said presser foot.

7. In combination a work-support, a presser foot, a gage movably mounted on said work-support and adapted to project 105 upwardly beyond its work contacting surface and into engagement with the work contacting surface of said presser foot and means to move said presser foot away from said work-support, said gage being adapted 110 to move upwardly and downwardly with said presser foot.

8. In combination, a work-support, a presser foot, and a gage pivotally mounted upon said work-support and adapted normally to project above the work contacting surface of said work-support, a portion of the front edge of said gage being inclined upwardly and forwardly from the work contacting surface of said work-support and 120 means to raise and lower said presser foot, said gage being adapted to move upwardly and downwardly with said presser foot.

9. In combination, a work support, a presser foot and a gage pivotally mounted 125 upon said work-support and adapted normally to project above the work contacting surface of said work-support, a portion of the front edge of said gage being inclined upwardly and forwardly from the work 130

contacting surface of said work-support for a portion of its length above said surface and then rearwardly and upwardly toward the work contacting surface of said presser foot and means to raise and lower said presser foot.

In testimony whereof I have hereunto set

my hand in presence of two subscribing witnesses.

AUSTIN D. RHODES.
